UNITED STATES PATENT OFFICE.

CECIL HAMELIN TAYLOR AND BOUDEWIJN B. NEUTEBOOM, OF DETROIT, MICHIGAN.

EXPLOSION-ENGINE.

1,135,074.

Specification of Letters Patent. Patented Apr. 13, 1915.

Application filed May 21, 1913. Serial No. 788,929.

To all whom it may concern:

Be it known that we, CECIL HAMELIN TAYLOR, a citizen of the United States, residing at Detroit, county of Wayne, State of Michigan, and BOUDEWIJN B. NEUTEBOOM, a subject of the Queen of the Netherlands, residing at Detroit, county of Wayne, and State of Michigan, have invented a certain new and useful Improvement in Explosions-Engines, and declare the following to be a full, clear, and exact description of the same, such as will enable others skilled in the art to which it pertains to make and use the same, reference being had to the accompanying drawings, which form a part of this specification.

Our invention relates to explosion engines and an object of our improvements is to provide an improved means for supplying heat to the walls of the intake passage. We secure this object in the device illustrated in the accompanying drawing, in which,

Figure 1, is a plan view of an apparatus embodying our invention and so much of an engine as is necessary to show its connection therewith. Fig. 2, is an elevation of the same, a part being broken away to show the interior construction. Fig. 3, is a detail sectional view.

a a indicate the cylinders.

b is the intake passage and *c* is a jacket surrounding the intake passage *b*.

i i indicates the exhaust passage. There are openings *e e* upon opposite sides of the jacket *c* and communicating with the interior thereof.

d is a conduit communicating with one of the passages *e* and with the interior of the exhaust passage *i*.

h is a conduit similar to the conduit *d* communicating with the other of the openings *e* and entering the exhaust passage *i* at a point adjacent to that with which the conduit *d* communicates. The conduit *d* ends in a nozzle *f* which is chamfered off so as to present an opening toward the direction from which the exhaust gases come. The conduit *h* terminates in the exhaust

passage *i* in a nozzle *g* chamfered in a direction to present its opening away from the direction from which the exhaust gases

come. There is a cock *j* in the conduit *h* by which the area of the passage through said conduit may be adjusted.

The operation of the above described device is as follows: Both of the conduits *d* and *h* being open, when the exhaust gases pass through the passage *i* some of said gases are forced through the conduit *d* into the jacket *c* and out through the conduit *h* and are discharged again into the exhaust passage *i* where they pass out with the rest of said gases. This action is secured by the different ways in which the nozzles *f* and *g* are chamfered. The effect of forcing the hot exhaust gases from the exhaust passage and leading them thereto may obviously be secured in other ways than by chamfering off the ends of said conduits in the exhaust passage as above described, but we have preferred this particular form. The area of opening and therefore the quantity of the exhaust gases passing through the conduit *h* may be regulated by the cock *j*.

What we claim is:

1. In combination with the exhaust passage of an engine, a heating jacket, a conduit communicating with the said exhaust passage and said jacket, a second conduit communicating with said jacket and said exhaust passage, the end of one of said conduits opening against a current of moving gases in said exhaust passage so that a portion of said gases shall be projected into said conduit, the second of said conduits opening into said exhaust passage in such a relative position that the gases shall not be projected into said second conduit.

2. In combination with the exhaust passage of an engine, a heating jacket, a conduit communicating with said exhaust passage and said jacket, a second conduit communicating with said jacket and said exhaust passage, the ends of said conduits being arranged adjacent to each other in said exhaust passage, the end of one of said conduits opening against the current of moving gases in said exhaust passage and the end of the other conduit opening away from said current of gases.

3. In combination with an exhaust passage of an engine, a heating jacket, a pipe communicating with said exhaust passage

and said jacket, a second pipe communicating with said jacket and said exhaust passage, the ends of said pipes extending through the wall of said exhaust passage approximately at right angles thereto and having their ends chamfered in opposite directions, substantially as and for the purpose described.

In testimony whereof, we sign this specification in the presence of two witnesses.

10

CECIL HAMELIN TAYLOR.
BOUDEWIJN B. NEUTEBOOM.
